PAGE 6

FIG. 6

FIG - 7

FIGURE 1 is a front perspective of a magnetic tape transport showing my new design;

FIGURE 2 is a front perspective of the design shown in FIGURE 1 with the cover removed;

FIGURE 3 is a front elevation of the design shown in FIGURE 2;

FIGURE 4 is a left-hand side elevation of the design shown in FIGURE 2;

FIGURE 5 is a right-hand side elevation of the design shown in FIGURE 2;

FIGURE 6 is a rear elevation of the design shown in FIGURE 2; and

FIGURE 7 is a plan of the design shown in FIGURE 2. I claim:

The ornamental design for a magnetic tape transport, substantially as shown and described.
